UNITED STATES PATENT OFFICE

THOMAS KATER, OF HAMILTON, CANADA.

IMPROVEMENT IN PIANO-FORTE AGRAFFES.

Specification forming part of Letters Patent No. **149,759**, dated April 14, 1874; application filed March 9, 1874.

To all whom it may concern:

Be it known that I, THOMAS KATER, of Hamilton, in the county of Wentworth and Dominion of Canada, have invented certain new and useful Improvements in Stringing Pianos, of which the following is a specification:

This invention relates to a novel mode of stringing pianos, whereby the supporting-bridge between the ordinary agraffes and tuning-pins and the bearing-pins of the curved central bridge are dispensed with. The invention consists in an agraffe, which is provided with an opening or openings for the passage of the strings, and with a transverse opening for the reception of a bearing pin or rod, said rod being designed to subserve the function of the ordinary supporting-bridge usually arranged in rear of the agraffes, but being located directly in the center, or within the agraffe, and beneath the string. A check or bend is formed in the same, so as to secure a double, or upward and downward, bearing, for imparting the requisite rigidity to the string, and augmenting its sounding qualities, and, furthermore, lessening the tendency of displacing or loosening the agraffes in tuning the strings. The invention further consists in forming an agraffe with a transverse opening, and with openings at right angles thereto, which vary in diameter or size, so as to cause the strings passing through the same to bear against the roof or apex of the smaller openings, and to be located at or about the center of the enlarged openings.

In the accompanying drawings, Figure 1 is perspective view of a portion of the frame of a piano-forte, showing the arrangement of the strings and agraffes. Fig. 2 is a view representing the check or bend in the string, and the openings in the agraffes, the latter being partly in section. Fig. 3 is a detached view of the agraffes, taken on opposite sides of the same, and through the center.

Heretofore it has been customary, in stringing pianos, to arrange, in respect to the tuning-pins, agraffes having openings for the passage of the strings, which serve, in connection with a bridge located in rear of the same, to support the wires, and to form the check or bend in the latter. This arrangement of parts is considered defective, as in tuning or tight-

ening the strings, and, in use, the agraffes are apt to be loosened or displaced by reason of the upward strain exerted upon the same by the strings, which is due to the passage of the same over the bearing-bridge. The passage of the strings between the ordinary pins of the curved center-bridge, to secure a lateral bearing or check in the strings, is also objectionable, for various reasons.

My invention is designed to remedy the defects above stated, and to furnish simple and effective means for stringing pianos; and, in carrying the same into practice, I make use of agraffes A, which are provided with enlarged heads, and with screw or other shanks for securing the same to the frame. The head of the agraffe is provided with one, two, or three string-openings, a, according to the number of strings which are employed to form a note; and, in addition to said openings, each agraffe is formed with a transverse opening, b, or one arranged at right angles to the string-openings. The agraffes are designed to be applied to the ordinary tuning block, plate, rail, or base B, which supports or carries the ordinary tuning-pins C, and the strings D are attached to the latter in the ordinary manner. The strings are passed through the openings in the agraffes located on the tuning-pin rail, and through correspondingly-shaped agraffes E, arranged on the curved center or sound-board bridge F of the piano, and from thence they are conducted to the ordinary hitching-pins G at the opposite side of the frame. The transverse opening in the agraffe is designed for the reception of a pin or rod, G', which passes directly through the center of the agraffe, beneath the string or strings, as shown in Figs. 1 and 2. The object of said pin or rod is to form a central bearing, or check, or bend in the wire; and it thus subserves the function of the ordinary bridge located between the agraffes or tuning-pins.

The openings in the agraffes for the passage of the strings vary in diameter or size at the sides of the central opening, so that when the pin or rod is passed through the latter the front of the wire is forced against the roof or apex of the small opening, while the opposite portion of the wire is located at or about the center of the enlarged opening. By this means an upward bearing is obtained in front, and a

downward bearing in the center, so that the necessary degree of rigidity or tension will be imparted to the string, and to form what is technically termed a "check." The agraffes are, by reason of the arrangement of the strings and transverse pin, not liable to be displaced or loosened in tuning or tightening the strings, and in use, as the strain is equalized by the double bearing-surfaces.

In contradistinction to the ordinary pins applied to the curved sound-board or center-bridge F for forming a check in the wire, I propose to arrange thereon the agraffes E, as heretofore described. The strings pass through the same in the same manner as in the agraffes of the tuning block, plate, rail, or base, and the pin or transverse rod is employed for a like purpose.

In the present instance, the series of agraffes on the curved center-bridge and tuning block, plate, rail, or base are reversed—that is to say, the small openings are, in one series of agraffes, located at the front, and, in the other, at the rear, as shown in Fig. 2.

An ordinary agraffe cannot be employed in connection with the center-bridge, as it lacks the means for forming a check or bend in the string; but an agraffe constructed according to my invention can be readily applied to secure the advantages previously stated.

Having thus fully described my invention, what I claim as new, and desire to secure by Letters Patent, is—

1. An agraffe for pianos, having one or more openings for the passage of the string or strings, and a transverse opening at right angles thereto for the reception of a pin, rod, or bridge, substantially as herein described.

2. The agraffe A, located on the tuning block, plate, rail, or base, having an opening or openings, *a*, for the string or strings, a transverse opening, *b*, and a pin or bridge, *G'*, passing through the latter to form a check in the string, and to secure a double bearing, substantially as herein described.

3. An agraffe for pianos, having one or more string-openings varying in diameter or size on opposite sides of a central transverse pin or bridge opening, substantially as herein described.

In testimony that I claim the foregoing I have hereunto set my hand this 9th day of March, 1874.

THOMAS KATER.
